Des Moines, Iowa

Application August 10, 1935, Serial No. 35,687

17 Claims. (Cl. 109—7)

Our invention relates to an improved device for the protection of banks and the like against burglary.

Heretofore a great deal of time and effort has been expended in the construction of bank vaults capable of withstanding explosives, drills and other means of breaking into the vaults, and also in the construction of complicated combinations and time locks and the like in an effort 10 to make it difficult or impossible for a burglar to open the vault.

Notwithstanding the generally accepted use of such devices in the banks there is at the present time an alarmingly large number of bank robberies, and a large number of them are accomplished as follows: The burglar, knowing the practical impossibility of him being able to gain access to the interior of the vault without aid, is in the habit of entering a bank and finding 15 a bank official who knows the combination of the lock or the other means for gaining access to the vault, and then the burglar threatens the bank official with the loss of his life unless the official opens the vault. Under such circumstances, obviously the official opens the vault and the burglar escapes with the valuables contained 20 in the vault.

The object of our invention is to provide a banker's safety unit of simple, durable and inexpensive construction, and by means of which and in the event that a burglar with a gun should threaten the life of the bank official unless the bank official opened the door leading to the vault, then the bank official could, by manipulating 25 the dial for opening the door to the vault, automatically close a sliding steel panel between himself and the burglar so that the burglar could not shoot the official, and at the same time securely trap the burglar within a small steel wall enclosure, and also at the same time automatically sound the alarm on the exterior of the bank so that the legal authorities could be notified of the attempted burglary and capture the burglar.

More specifically, it is our object to provide 30 in a bank building a revolving door at the entrance to the bank, and a steel walled passageway leading from the customers' lobby of the bank to the bank vault, and through which every one entering the bank vault must pass, and also 35 to provide in said passageway means whereby a burglar with a gun, threatening a bank official and demanding that he open the door to the vault, could be locked in a steel walled enclosure, and at the same time a revolving door leading 40 to the bank could also be automatically locked 45

by the bank official within the steel walled enclosure so that when the alarm is given and the legal authorities arrive at the bank, not only the particular burglar threatening the bank official could be captured, but his associates who 5 may be there for the purpose of preventing interference by other customers would also be locked within the bank and thereby easily captured by the authorities.

More specifically, it is our object to provide 10 a steel walled passageway for entrance to the bank vault, of such size and shape that one man only could stand in the space within the passageway nearest the vault, so that the bank official who knew the means for opening the 15 door leading from the passageway to the vault must necessarily occupy this space, and further to provide a sliding door in this passageway substantially invisible to those within the passageway, and to provide means whereby the bank 20 official may, in an apparent attempt to open the door leading from the passageway to the vault, automatically actuate a power operated mechanism for quickly sliding the metal door between himself and the burglar to thereby prevent the 25 burglar from carrying out his threat on the life of the bank official; and further in this connection, it is our object to provide means whereby, 30 in the event that the burglar should attempt by mechanical devices to prevent the closing of said sliding door, the wall of the passageway toward which the sliding door moves to closed position will automatically yield in such manner as to 35 eject any such mechanical devices for preventing the closing of the door.

Our invention consists in the construction, arrangement and combination of the various parts of the device, whereby the objects contemplated are attained, as hereinafter more fully set forth, pointed out in our claims, and illustrated in the 40 accompanying drawings, in which:

Figure 1 shows a horizontal, sectional view of a bank building containing our improved banker's safety unit with the top of the walled passage removed.

Figure 2 shows a vertical sectional view taken longitudinally through a steel walled passageway leading to the bank building and illustrating the sliding door in its closed or partly closed positions.

Figure 3 shows an enlarged detail vertical sectional view illustrating the valve devices on the exterior of the bank building for releasing the locked doors within the bank, taken on the line 3—3 of Figure 1.

Figure 4 shows a detail sectional view taken on the line 4—4 of Fig. 1 illustrating the construction of the foot operated valve openers for automatically locking the revolving door to the bank entrance.

Figure 5 shows a perspective view illustrating the steel walled passageway and its connected parts.

Figure 6 shows a detail perspective view, partly in section, illustrating the mechanism for locking the revolving door.

Figure 7 shows a detail view in vertical section illustrating the means for locking and releasing the side wall door.

Figure 8 shows an enlarged detail view, partly in section, illustrating the mechanism for closing the sliding door and for unlocking the door leading from the steel walled passageway to the bank vault.

Figure 9 shows an enlarged detail view, partly in section, illustrating the mechanism for controlling the valve in the air line which operates the sliding door; and

Figure 10 shows an end elevation of same with one of the slide bars in the notch in the disc and in position for permitting the passage of air through the air line to close the sliding door.

Figure 11 shows a detail sectional view taken on the line 11—11 of Figure 8.

Figure 12 is a detail sectional view illustrating one of the loops 54 in section and the manner in which the hooks on the lever 58 engage the same to lock the door 17 in its closed position.

Referring to the accompanying drawings, we have used the reference numeral 10 to indicate generally the walls of a bank building and 11 to indicate generally the revolving door at the street entrance to the bank building. Surrounding the revolving door are the walls 12 forming the customers' lobby. In the following specification and claims, we have referred to the bank vault, and by this we mean all or any part of the space within the bank walls except that part contained within the walls of the customers' lobby.

For providing communication between the customers' lobby and the interior of the bank building or vault we have provided a steel walled passageway, the walls of which are indicated generally by the reference numeral 13. In one of the side walls of this passageway there is a door 14 (see Figure 1) leading to one end of the said passageway from the customers' lobby, and at the opposite end of the passageway there is a spring closed door 15 leading into the vault from the passageway, and between these two doors there is a sliding door 16. This sliding door extends through a slot in the steel walled passageway, and when in open position, the edge of the door substantially fills the slot and the door is thereby rendered substantially invisible or at least inconspicuous. In this connection it should be explained that the relative sizes of the various parts of the steel walled passageway are of importance, and it is desirable that the side walls 13 of the passageway adjacent the door 15 are so close together that one man only can stand in these spaces between the side walls, and it is also important that the sliding door be so positioned that one man only can stand in the space between the door 15 and the sliding door 16.

On the side of the steel walled passageway toward which the sliding door 16 moves to closed position, we have provided a spring closed hinged panel 17 so constructed and arranged that if 75 when the sliding door 16 is being moved to closed

position a man's body should be interposed between the sliding door and the hinged panel 17, the hinged panel will move a slight distance so that the body, or portions thereof, may be moved into the space within the steel walled passageway adjacent the door 14, or, more particularly, in the event that the burglar should attempt to prevent the closing of the sliding member 16 by interposing between it and the adjacent steel wall of the passageway a block or brace or other object, the panel 17 would swing outwardly far enough to permit this brace or the like to slide off of the panel without preventing the closing of the sliding door. Springs 17b are connected to the panel 17 and mounted on the ceiling of the 15 passageway to normally return the panel to closed position.

The specific construction of the steel walled passageway is as follows: The entrance door 14 may be opened and closed at will, and anyone within the passageway between the sliding door 16 and the door 14 may enter the customers' lobby. The sliding door 16 is provided with an outer flange 18, in which there is a slot which receives a guide arm 19 secured to the outer 25 surface of the steel walled passageway, and another guide device 20 supports the bottom of the slide door so that it will freely and easily move in a straight line. Secured to the outer end of the slide door is a piston rod 21 extended 30 into a cylinder 22 and provided with a piston not shown, so that when air is admitted into the opposite end of the cylinder 22 (see Figure 1) the slide door is forced to closed position, and when compressed air is admitted to the other end of 35 the cylinder the slide door is moved to open position. The hinged door 15 is preferably provided, as shown in Figure 2, with a bullet proof window 23 of ordinary construction.

On the outer surface of the steel walled passageway adjacent the closed edge of the door 15 is a slide bar 24 (see Figure 5) having hooks 25 thereon to engage lugs 26 on the door 15. A spring 27 is provided to normally hold the slide bar 24 downwardly, and the hand operated lever 45 28 on the exterior of the steel walled passageway is provided for raising the hooks 25 and releasing the door 15 so that this door may always be readily and easily opened by a person wishing to pass from the vault portion of the bank enclosure 50 into the passageway.

The door 15 may also be opened from the interior of the passageway, and from the same point manually controlled means may be operated to cause the closing of the sliding door 16, 55 and also to cause the locking of the revolving door. This means comprises a dial 29, of ordinary construction, mounted in the upper portion of the passageway adjacent the door 15. This dial is fixed to a shaft 30 which is connected to a bevelled pinion 31 in mesh with a bevelled pinion 32, and this bevelled pinion 32 is connected to a cylinder 33 which rotates in unison with the bevelled pinion 32. This cylinder 33, as shown in Figure 8, is provided with notches 34 in its periphery. 60

Mounted above the cylinder 33 is a rock shaft 35 provided with a crank arm 36 connected by a rod 37 to the slide bar 24, and on the shaft 35 another crank arm 38 is provided (see Figure 5), for purposes hereinafter made clear.

For the purpose of actuating the mechanism by which the sliding door 16 is operated we have provided on the rock shaft 35 two crank arms 40 extended downwardly in the direction away from the door 15, as shown in Figure 5, and fixed to 75

the outer ends of these crank arms 40 is a support 41. This support 41 carries a latch bar 42 so shaped that when moved downwardly it may enter the notch 34 in the cylinder 33, and slidably connected with the latch bar 42 is a second latch bar 43 yieldingly held to its downward limit by a spring 44, and also capable of entering the notch 34 if the cylinder 33 is properly positioned below it. This latch bar 43 has an extending arm 45 (see Figure 9) arranged adjacent to a release valve 46 in the compressed air pipe line 47, hereinafter described. As shown in Figure 10 the cylinder 33 has been rotated to position with the notch 34 directly under the latch bar 43, and this latch bar 43 has been moved downwardly by its spring 44 into the notch in the cylinder 33.

Within the interior of the steel walled passageway there is a hand lever 48 (see Figure 8) connected by a link 49 to a piston 50 mounted in a cylinder 51, in which there is a spring 52 for normally holding the piston 50 in its elevated position. This piston 50 is connected by a rod 53 with the crank arm 40 to normally hold the frame 41 in its elevated position. A second similar piston 50 and cylinder 51 are provided to connect with the other one of the crank arms 40 to cause the frame 41 to move upwardly and downwardly and remain in horizontal position.

By means of the construction thus described, and assuming that the operator manipulates the dial 29 in such manner as to bring the slot 34 in the cylinder 33 directly under the bar 43, then if the operator pulls the lever 48 the bar 43 will enter the slot 34 and thereby depress the valve 46 to permit passage of air through it and thereby operate mechanism which will automatically close the door 16 and give an alarm. If, however, the dial 29 is manipulated to turn the cylinder to a position where the slot 34 is directly under the bar 42, then when the operator moves the lever 48 downwardly the bar 42 will enter the slot 34 and rock the shaft 35 and elevate the crank arm 36, thus moving the latch bar 43 upwardly and releasing the door 15 which may be swung outwardly so that the operator may freely enter the interior of the bank structure containing the vault or other valuables.

In the event that the slide door 16 is moved to closed position to thereby separate a bank official within the passageway adjacent the door 15 from a burglar within the passageway at the end toward the door 14, it is desirable that the door 17 be held closed so that a burglar within the customers' lobby cannot open the door 17 and thereby obtain access to the bank official. For this purpose we have provided at the upper and lower ends of the door 17, as shown in Figure 7, a loop 54 at the top and another corresponding loop 54 at the bottom. These loops extend inwardly below the floor 55 and above the ceiling 56 of the passageway, for purposes hereinafter made clear.

Mounted on top of the ceiling 56 is a bracket 57 to which is pivoted a lever 58, and pivoted below the floor 55 is a corresponding lever 59. These levers have hooks at their outer ends, and the other ends are connected with a link 60. This link is extended upwardly above the passageway and is connected to a bell crank lever 61 (see Figure 5) which is connected to a rod 62; a compression spring 63 is mounted on said rod and said rod also connects with the bell crank lever 61. This spring 63 normally holds the link 60 in its lowered position so that the hooked levers 58 and 59 are thereby held out of engagement with

the loops 54 and the door 17 may be opened. However, when the rock shaft 35 is turned to such position as will, by permitting the bar 43 to enter the notch 34 of the drum 33 and the valve 46 to be actuated to permit air to enter the pipe 72 and the cylinder 22, actuate the mechanism for closing the slide door 16, the crank lever 61 is moved upwardly and the hooked levers 58 and 59 will engage the loops 54 and lock the door 17 shut.

We preferably operate the various working parts of our invention by means of compressed air, and we have provided a compressed air storage tank 70 from which a pipe 71 leads to a pipe 72 which communicates with a pipe 73, shown in Figure 6, leading to a cylinder 74 directly over the revolving door hereinafter described. This pipe 72 also extends to the outer end of the cylinder 22, before described, and between the revolving door and the cylinder 22 there is a one way check valve 75. Also connected to the tank 70 is a pipe 71a. A pipe 76 communicates with the pipe 71a and leads to a valve of ordinary construction, shown in Figure 3, and located on the exterior of the building (see Figure 1). The pipe 77 communicates with the pipe 72 and also communicates with said valve. The pipe 78 communicates with the said valve and leads to the inner end of the cylinder 22, and this pipe 78 also communicates with the bottom of the cylinder 74, which will be hereinafter described.

The said valve shown in Figure 3 comprises a cylindrical valve casing 79 and a rotary valve body 80 within the casing. The valve body is provided with two passageways 81 and 82, and the casing is provided with four inlet and outlet passageways. When the valve is in the position shown in Figure 3, then compressed air may pass through the pipe 76 and out through the pipe 78 to the inner end of the cylinder 22 for normally holding the slide door 16 open, and at the same time air may pass through the pipe 77 and out through the exhaust port 83, but when the valve 80 is moved to a different position this passage of air through it is prevented.

The revolving door has heretofore been described generally as a revolving door 11, and the door itself is of the ordinary revolving door type. In addition to this, we have provided at the top of the door a cylindrical rack 84, the teeth thereof extending inwardly. On the top of the revolving member of the door we have provided two spring actuated ratchets 85, with their inner ends slightly spaced apart and with springs 86 normally holding the ratchets 85 inwardly out of engagement with the rack bar 84, normally permitting rotation of the revolving door. The cylinder 74, before described, communicates with the air pipe 73, and below the cylinder is the exhaust pipe 78. Within the cylinder is a piston 87, and connected to the piston is a cone wedge 88 capable of entering between the inner ends of the ratchets 85. Hence, when the cone wedge 88 is down, the revolving door is locked, and when up, the springs 86 push the ratchets 85 away from the rack 84 and permit the revolving door to freely rotate.

Thus it will be seen that the door may be automatically locked by manipulating the dial 29 to cause the cylinder 33 to rotate to position with the notch 34 beneath the bar 43, after which the operator may lower the lever 48 against the resistance of the springs 52 and 63, causing the valve stem 46 to be actuated and air under pressure to be admitted to the pipes 71 and 72 and 75

to the cylinder 22, at which time the door 16 is closed. Air will also flow through the pipe 72, past the cylinder 22, through the check valve 75 to the pipe 73 and into the upper end of the cylinder 74, causing the piston 87 to be lowered and the door 11 locked against rotation, in the manner above described. The door 11 may then be unlocked at such times as hereinafter set forth, by simply rotating the valve 80 to its exhaust position as shown in Figure 3, thus exhausting the pipes 77 and 78, which takes place with the valve 47 closed. Air from the pipe 76 under pressure from the tank 70 will then enter the pipe 78 through the passage 81 of said valve and cause the piston 87 to be elevated and the door 11 unlocked, at the same time causing the piston of the cylinder 22 to be moved to its normal position with the door 16 opened. The valve 80 may then be returned to its normal position with the parts connecting the pipes 77 and 76 closed. In this connection it should be noted that the door 15 is always maintained in a closed and locked position except when bank officials are passing through the walled passage, at which time the door 15 may be unlocked by actuating the lever 28 from position within the vault or by actuating the dial 29 and moving the notch 34 of the cylinder 33 to position beneath the bar 42, then actuating the lever 48 to unlatch said door, in the manner before described. When the official is positioned within the walled passage these opening and closing operations take place without actuating the door 16 or locking the revolving door 11, thus permitting the bank official to travel freely through the walled passage. It sometimes happens that it is desired to lock the door 11 without closing the door 16 and at such times as the bank official is not forced to enter the walled passage. To accomplish this we have provided means whereby the revolving door may be placed in locked position by the operators at various parts within the bank building without closing the door 16, and for this purpose we have provided a pivoted foot rail 89, shown in Figure 4, with its upper end connected to a valve 90 in the pipe 72a leading to the pipe 77, which pipe 72a is connected to the air supply pipes, 71 to 71a, and 76 by means of a short pipe 91. This foot rail 89 is yieldingly held downwardly by a spring 92, then when it is desired to operate it, the operator places his toe under the foot rail 89, thus opening the valve and permitting air being discharged from the pipe 71a to pass to the pipe 72a, which will enter the cylinder 74 through the pipe 73 and cause the piston 87 to be moved downwardly and the ratchets 85 to be moved to locking position. The check valve 75 serves to prevent air from the pipe 76 entering the pipe 72 and the piston in the cylinder 22 to be maintained inoperative. The door 11 will then remain locked until the valve 80 is moved to its exhaust position. If the rail 89 is lowered, the valve 90 will close, trapping the air under pressure in the pipe 72a. Movement of the valve 80 to exhaust position will permit the pressure in the pipe 72a to be reduced to atmospheric pressure.

In practical use, and assuming that a bank holdup of the kind now extremely common is attempted on a bank equipped with our improvement, let it be assumed that one robber equipped with a gun captures a bank official within the customers' lobby and that other robbers are stationed within the customers' lobby as assistants; and assuming that the robber demands that the bank official open the vault or other receptacle

for the bank's valuables, and places the gun close to the bank official for enforcing this demand, under such circumstances the bank official must open the door 14 and enter the passageway leading to the vault. The end of the 5 passageway adjacent the door 15 is so narrow that the body of the bank official only can enter between its side walls, and the robber must necessarily stand at the rear of the passageway. Then the banker may manipulate the dial 29 in 10 such manner as to actuate the sliding door 16 so that this smooth sliding door is rapidly forced between him and the burglar, and the instant that this is done, the banker is secure from gun fire from the burglar, whereupon the banker may 15 then proceed to sound an alarm in any ordinary manner, not shown. During this time that the bank official is within the passageway and the door 16 is closed, neither the burglar who followed him in to the passageway nor any assistants who might be within the customers' lobby, may in any way injure the banker because the banker is within the steel walled passageway. When the robbers know that they have thus been foiled in their attempt they would naturally seek to escape through the revolving door, the only exit from the customers' lobby. This, however, is impossible because the revolving door has been automatically locked at the time the door 16 was closed, and the robber and his 20 associates are all securely locked within the customers' lobby and cannot injure the bank officials who are behind the partition forming the customers' lobby. When police officials arrive they can readily and easily manipulate the valve 25 80 on the exterior of the bank building to release the revolving door, so that they may enter and capture the burglars.

During the ordinary procedure within the bank there is no particular difficulty in having 40 the bank officials enter from the customers' lobby into the bank vault compartment because the door 14 freely swings open and closed, and the door 15 may be opened very readily and quickly by having the bank official manipulate the dial 45 29 so that it permits the release of the door 15 which may then be opened by moving the lever 48, and when the bank officials are passing from the vault compartment to the customers' lobby, the door 15 is easily opened by manipulating the 50 lever 28 and the door 14 freely swings open.

In the accompanying claims we have referred to the bank building walls, the customers' lobby, the vault compartment, and the like, as applied to the use of our invention in connection with 55 banks only, but we do not wish to be understood as limiting our invention as applied to banks having vaults because, obviously, the same mechanism may be successfully employed for protecting other valuables.

We claim as our invention:

1. In a banker's safety unit, the combination of a passageway compartment leading to a bank vault, a door in said passageway for admission to and from the passageway and another door in said 65 passageway for admission to and from the bank vault, the walls of said passageway adjacent the said door for admission to the bank vault being spaced apart sufficiently to admit the body of one man only, and a third door normally open 70 but, when closed, extending across the passageway and separating the space for one man at the end of the passage nearest the vault from the space at the other end of the passageway.

2. In a banker's safety unit, the combination 75

5 of a passageway compartment leading to a bank vault, a door in said passageway for admission to and from the passageway and another door in said passageway for admission to and from the bank vault, the walls of said passageway adjacent the said door for admission to the bank vault being spaced apart sufficiently to admit the body of one man only, and a third door normally open but, when closed, extending across 10 the passageway and separating the space for one man at the end of the passage nearest the vault from the space at the other end of the passageway, means for automatically closing said third door; and a control device for said closing means 15 accessible to an operator within the passageway and adjacent the door for admission to the bank vault.

3. In a banker's safety unit, the combination of a passageway compartment leading to a bank 20 vault, a door in said passageway for admission to and from the passageway and another door in said passageway for admission to and from the bank vault, the walls of said passageway adjacent the said door for admission to the bank 25 vault being spaced apart sufficiently to admit the body of one man only, and a third door normally open but, when closed, extending across the passageway and separating the space for one man at the end of the passage nearest the vault 30 from the space at the other end of the passageway, means for automatically closing said third door, a control device for said closing means accessible to an operator within the passageway and adjacent the door for admission to the bank 35 vault, means for locking the said door for admission to the bank vault, and a lock releasing means on the interior of the passageway adjacent the door for admission to the bank vault.

4. In a banker's safety unit, the combination 40 of a passageway compartment leading to a bank vault, a door in said passageway for admission to and from the passageway and another door in said passageway for admission to and from the bank vault, the walls of said passageway adjacent the said door for admission to the bank vault being spaced apart sufficiently to admit the body of one man only, and a third door normally open but, when closed, extending across 45 the passageway and separating the space for one man at the end of the passage nearest the vault from the space at the other end of the passageway, and a manually operable control device located within the passageway adjacent the door for admission to the bank 50 vault and compressing means which in one position will release mechanism for closing said third door and in another position will permit the opening of the door for admission to the bank vault.

60 5. In a banker's safety unit, the combination of an enclosed passageway, a door at each end of the passageway, and a sliding door which, when closed, divides the passageway into two separate compartments.

65 6. In a banker's safety unit, the combination of an enclosed passageway, a door at each end of the passageway, a sliding door which, when closed, divides the passageway into two separate compartments, power operated means for closing said sliding door, and means located within the passageway adjacent the door at one end for releasing said power operated means to close the sliding door.

70 7. In a banker's safety unit, the combination 75 of an enclosed passageway, a door at each end

of the passageway, and a sliding door which, when closed, divides the passageway into two separate compartments, the wall of the passageway toward which the sliding door moves to closed position being hinged to thereby swing 5 partially open and release an object interposed between the sliding door and said wall portion.

8. In a banker's safety unit, the combination 10 of an enclosed passageway, a door at each end of the passageway, a sliding door which, when closed, divides the passageway into two separate compartments, the wall of the passageway toward which the sliding door moves to closed 15 position being hinged to thereby swing partially open and release an object interposed between the sliding door and said wall portion, and yielding means for normally holding said wall portion in closed position.

9. In a banker's safety unit, the combination 20 of a passageway compartment leading to a bank vault, a door in said passageway for admission to and from the passageway and another door in said passageway for admission to and from the bank vault, the walls of said passageway adjacent the said door for admission to the bank 25 vault being spaced apart sufficiently to admit the body of one man only, and a third door normally open but, when closed, extending across the passageway and separating the space for one man at the end of the passage nearest the vault 30 from the space at the other end of the passageway, power operated means for closing said third door and manually controlled means located at the exterior of the passageway for releasing said power operated closing means. 35

10. In a banker's safety unit, the combination 40 of an enclosed passageway, a door at each end of the passageway, a sliding door which, when closed, divides the passageway into two separate compartments, means for automatically locking said sliding door in its closed position, and manually operated means exterior to the passageway for unlocking said sliding door.

11. A banker's safety unit comprising a vault 45 compartment, a customers' lobby walled off from the vault compartment, there being a street entrance opening into the customers lobby, and a walled passageway between the customers' lobby and the vault compartment, a door at said street entrance, and a door within said passageway, and manually controlled means whereby an operator within the passageway may lock 50 the street entrance door to prevent exit from the customers' lobby and at the same time close the door within the passageway to prevent entrance to the vault compartment. 55

12. A banker's safety unit comprising a vault compartment, a customers' lobby walled off from the vault compartment, a revolving door for entrance to and exit from the customers' lobby, 60 means for locking the revolving door in various positions of its movement, a passageway communicating between the customers' lobby and the vault compartment, a sliding door for closing said passageway, power operated means for simultaneously closing said sliding door and locking 65 said revolving door, and a manually operated device within said passageway for controlling said power operated means.

13. In a banker's safety unit, the combination 70 of a passageway having entrance and exit openings at opposite end portions, one of its side walls being formed with an upright slot, a metallic slide door normally at one side of the passageway with one edge in said slot. 75

14. In a banker's safety unit, the combination of a passageway having entrance and exit openings at opposite end portions, one of its side walls being formed with an upright slot, a metallic slide door normally at one side of the passageway with one edge in said slot, and a yieldable panel at the side of the passageway wall toward which the advanced edge of the sliding door moves when closing.
15. In a banker's safety unit, the combination of a walled passageway, a door at one end of the passageway, a sliding door extended through the wall at one side of the passageway, a dial within the passageway between said doors, power operated means for closing the sliding door at one end of the passageway in closed position, and means operated by said dial when in one position for operating said means for closing the sliding door, and when in another position for releasing the locking means for the door at the end of the passageway.
16. In a banker's safety unit, the combination of a walled passageway, a door at one end of the passageway, a sliding door extended through the wall at one side of the passageway, a dial within the passageway between said doors, power operated means for closing the sliding door at one end of the passageway in closed position, means operated by said dial when in one position for operating said means for closing the sliding door, and when in another position for releasing the locking means for the door at the end of the passageway.
17. In a banker's safety unit, the combination of a passageway leading to a bank vault and having door openings at opposite sides, a door for each of said openings, manually controlled means on the interior of the passageway for opening the door leading to the vault, and means automatically operated by said manually controlled means for holding in closed position the door leading into the passageway.
